UNITED STATES PATENT OFFICE.

OTTO GOTTSCHALK, OF BUENOS AIRES, ARGENTINA.

RULER.

Application filed May 9, 1923. Serial No. 637,872.

To all whom it may concern:

Be it known that I, OTTO GOTTSCHALK, a citizen of Argentina, residing at Buenos Aires, have invented a new and useful Ruler, 5 of which the following is a specification.

This invention has reference to measuring instruments, and more particularly to an instrument especially designed for the mechanical calculation of values such as stresses and strains, bending moments, point of inflection in complicated structural designs.

The primary object of the invention is to provide an instrument which may be used 15 for the determination of the influence line or elastic curve of a beam, under certain loads.

Another object of the invention is to provide a device of this character including a 20 flexible member and a plurality of adjustable supports engaging the flexible member, whereby the supports may be adjusted to bend the flexible member in a manner to simulate curves of a beam, subjected to certain loads.

Another object is to provide an instrument for drawing curves.

With the foregoing and other objects in view which will appear as the description 30 proceeds, the invention resides in the combination and arrangement of parts and in the details of construction hereinafter described and claimed, it being understood that changes in the precise embodiment of the 35 invention herein disclosed, may be made within the scope of what is claimed, without departing from the spirit of the invention.

Referring to the drawing:—

Figure 1 is a fragmental plan view of 40 a device constructed in accordance with the invention.

Figure 2 is a sectional view taken on line 2—2 of Figure 1.

Figure 3 is a sectional view taken on line 45 3—3 of Figure 2.

Figure 4 is a sectional view taken on line 4—4 of Figure 2.

Figure 5 is a plan view disclosing the 50 flexible member in one position and disclosing the line of deformation.

Figure 6 is a plan view disclosing the flexible member as moved to a position to illustrate another line of deformation.

Figure 7 is a modified form of adjustable 55 bar and flexible member engaging device.

Figure 8 is another modified form of the invention.

Figure 9 is a further modified form of the invention.

Referring to the drawings in detail, the 60 device includes a body portion or ruler section 5 which is relatively long and formed with cut out portions in one surface thereof, and disposed adjacent to its side edges, defining ribs 6.

Mounted for movement longitudinally of the body portion 5 are a plurality of carriages 7, each of which being provided with downwardly and inwardly extended flanges 8 that engage the under surfaces of the 70 flanges 6 to secure the carriages to the body 5. As shown, the upper surfaces of these flanges are formed with upwardly and inwardly extended flanges 9 that lie in spaced relation with the upper surface of the body 75 portion 5 to provide guideways for the movable bars 10.

As shown by Fig. 5, these bars 10 are adjustable with respect to the carriages and move transversely of the body portion 5, securing screws 11 being provided and designed to extend through portions of the carriage to contact with the body portion or ruler section 5 to secure the bars in their 80 positions of adjustment.

Secured to each bar 10 is a rib 11' disposed intermediate the side edges of the bar 10, one end of each rib being provided with spaced fingers 12 between which the flexible member 13 may be held in defining a curved 90 line to illustrate a line of deformation of a beam.

Pulleys indicated at 14 are supported adjacent to one edge of the body portion 5 of the rule and disposed on opposite sides of the bar 10 associated therewith. A pulley 15 is carried by each bar 10, the pulleys being designed to accommodate the cord 16 which moves thereover, the arrangement of the pulleys being such as to cause the cord member 16 to exert a pull on the members 10 when a pull has been exerted on the cord 16 by means of the weights 17 secured at the ends of said cord.

In order that the carriages 7 and bars 10 will be held against movement, after they have been properly adjusted, set screws 11 are provided, which have their inner ends contacting with the body portion 5 where the same may be moved to set up a binding 110

action between the carriages, members 10 and body portion 5.

The ribs 11' are formed with teeth 18 disposed on the upper surfaces thereof, which 5 teeth may be used in connection with gears mounted above the carriages 7, whereby the bars 10 may be adjusted in a horizontal direction.

As shown by Fig. 7 of the drawings, a 10 bar is indicated at 25, which bar is provided with an arm 26 at its outer end, which arm is pivotally connected to the bar 25 at 27.

The outer end of the arm 26 as shown by Fig. 7 extends downwardly and supports the 15 bars 28 that are disposed in spaced relation with each other to grip the flexible member 29 therebetween. In the form of the invention illustrated in Fig. 8, a pair of bars 30 are pivotally supported at the outer end of 20 the bar 31 as at 32, the bars 30 being designed to grip a flexible member 33 therebetween.

From the foregoing it will be seen that the 25 flexible member when supported by the adjustable means as shown by Figs. 7 and 8 of the drawings, may be held at various angles with respect to the bar supporting the same.

In the form of the invention as shown by Fig. 9 of the drawings, it will be noted that 30 the movable bars 40 may be adjusted at angles with respect to the body portion 41 on which body portion is positioned a carriage 42 which is of a modified form.

The carriage 42 is formed with suitable 35 flanges embracing portions of the body portion 41, the bolt 43 that extends through the body portion 41 and bar 40 being designed to secure the bar 40 to the body portion 41.

An elongated opening 44 is provided in 40 the bar 40 to accommodate the bolt 43 and permit of such adjustment of the bar 40 with respect to the body portion 41.

In the use of the device, reference will be had to Fig. 1 of the drawings, wherein the 45 line indicated at A represents a beam line which is laid out in a suitable scale preferably on millimeter paper. The bars 10 are now adjusted to bring the outer ends of the ribs 11' to positions directly over the line, whereupon the flexible member 13 is passed 50 between the fingers 12 and adjusted to a position directly over the line. To ascertain the elastic curves for the bearing pressure, certain bars 10 are secured against movement with respect to the support while the remaining bars 10 are free to move under the weight of the weights 17 carried at the 55 ends of the flexible members 16.

Since portions of the flexible cord 16 are 60 positioned over the pulleys 14 and 15 with weights 17 secured thereto, it is obvious that the weights 17 tension flexible cord 16 and the movable members 10 are moved, and member 13 is bent until the weight 17 and the tension of the member 13 are balanced,

thereby defining a curved line to illustrate a line of deformation of a beam.

To further illustrate the use of the device, let A—B be a straight continuous horizontal beam over supports 1, 2 and 3 loaded in the 70 second span viz, between supports 2 and 3 with a concentrated load P and if it is desired to know the reaction R² upon support 2 and R, at support 1, the flexible member 13 is placed over the axis of the beam AB, 75 holding it at the points of support by means of the slides of the device as indicated by the drawings.

In order to find R² we displace the second 80 slide from the left any distance, for example, distance s in vertical direction to AB. The flexible member 13 will bend automatically into the elastic curve C. At load P the ordinate of the obtained curve is y, then we have immediately the reaction produced by 85

$$P:R^2 = \frac{y}{s} P.$$

If it is desired to determine the reaction at the exterior support 1 the slide is displaced to the left vertically to A—B to any distance for distance s' holding the flexible member in original position at all other points of support, as shown by Fig. 5. We then automatically have the elastic curve of C₁. Let y' be the ordinate at load P in Fig. 5 of that elastic curve, then the reaction R₁ produced by P at left support results immediately R₁ = $-\frac{y'}{s'} P$ negative because y' is on the opposite side of axis A—B with relation to the displacement s'. 90 95 100

Having thus described the invention, what is claimed as new is:—

1. In a device of the character described, 105 an elongated body portion, a plurality of carriages movable longitudinally of the body portion, bars movable transversely of the carriages and supported thereby, ribs formed on the bars and having ends extended beyond the bars, fingers on the extended ends of the ribs, a substantially wide flexible member adapted to be held between the fingers, said bars adapted to be moved to bend the flexible member, and means for securing the bars in their positions of adjustment. 110 115

2. In a device of the character described, 120 an elongated body portion, carriages movable longitudinally of the body portion, members movable transversely of the carriages, a flexible member adapted to be gripped by the movable members to bend the flexible member at various points, means for securing the movable members to the carriages, and means for securing the carriages to the body portion. 125

3. In a device of the character described, 130 an elongated body portion, carriages movable longitudinally of the body portion, lat-

erally movable members mounted on the carriages, gripping members on the laterally movable members, a flexible member adapted to be gripped by the gripping members, said movable members adapted to be adjusted to bend the flexible member, means for securing the movable members in their positions of adjustment, and means for securing the carriages to the body portion.

10 4. In a device of the character described, an elongated body portion, a carriage movable longitudinally of the body portion, movable members mounted on the carriages, and adapted to be adjusted laterally with respect to the body portion, a flexible member, means for gripping the flexible member and transmitting movement of the movable members to bend the flexible member, means

for automatically moving the laterally movable members.

5. In a device of the character described, an elongated body portion, carriages mounted for longitudinal adjustment on the body portion, laterally movable members having fingers, supported by the carriages, a flexible member adapted to be gripped by the fingers and moved to bend the same at various points throughout its length, rollers mounted on the carriages, rollers mounted on the movable members, a cord adapted to pass over the rollers to exert a pull on the movable members, and weights at the ends of the cord for tensioning the cord.

In testimony that I claim the foregoing as my own, I have hereto affixed my signature.

OTTO GOTTSCHALK.
